UNITED STATES PATENT OFFICE.

CLIFTON T. CHAPPELL, OF MACON, GEORGIA.

CAR-COUPING.

SPECIFICATION forming part of Letters Patent No. 340,762, dated April 27, 1886.

Application filed December 9, 1885. Serial No. 185,142. (No model.)

To all whom it may concern.

Be it known that I, CLIFTON T. CHAPPELL, of Macon, in the county of Bibb and State of Georgia, have invented a certain new and useful Improvement in Car-Couplings, of which 5 the following is a specification.

This invention relates to certain improvements in that class of car-couplings by which the cars to which the couplings are attached 10 may be automatically coupled when the cars come together, the coupling being so arranged 15 that the cars may be uncoupled without entering the space between them.

The object of this invention is to simplify 15 the construction of the coupling-pieces, and at the same time to render them efficient in operation; and to this end the invention consists 20 of a pair of coupling-jaws pivotally connected to a draw-head, said jaws being formed so that when held together there is a spherical recess 25 back of a bell-shaped mouth-piece, the jaws being held together by a locking-dog, which is retracted at the time of coupling or uncoupling, but which after the cars are coupled is held between the heels of the coupling-pieces by a spiral spring.

The invention further consists of certain other details of construction and combination of parts, which will be hereinafter explained. 30 Reference is to be had to the accompanying drawings, forming a part of this specification, in which similar letters of reference indicate corresponding parts in all the views.

Figure 1 is a view of a portion of one end of 35 an ordinary form of freight or box car with my improved coupling applied thereto. Fig. 2 is a view of the side of the draw-head and coupling removed from the car. Fig. 3 is a 40 view in vertical cross-section taken on line xx of Fig. 2. Fig. 4 is a view of the connecting-link between the locking-dog and the operating-lever. Fig. 5 is a longitudinal vertical sectional view of two of the couplings, the parts being represented in the positions 45 they assume as the cars are approaching and the ball of the coupling-link has just struck upon the jaw of the coupling; and Fig. 6 is a similar view representing the parts as they appear after the cars have approached still 50 closer.

Referring now to the drawings just described, A represents the draw-bar, formed

with an enlarged head, A', in which there is a recess, a , said recess being rectangular at its inner end, but being formed with beveled 55 sides as it approaches the mouth of the head. Within this recess a there are pivotally mounted two coupling-jaws, B and B', each jaw being formed with a hemispherical recess, b , and a flaring mouth-piece in the shape of one half 60 of an ordinary form of bell, there being a shoulder, c , between the parts, as clearly shown in Figs. 5 and 6.

Back of the hemispherical portion of the coupling-jaws each jaw is provided with a 65 lug or heel, f , which fits within the rectangular portion of the recess a , the jaws being held in place by pivot pins or bolts e , and each heel f being formed with a notch, so that when the two jaws are in the position 70 shown on the left in Figs. 5 and 6 there will be a space or recess, i , between the heels, which may be entered by a locking-dog, C.

In order that the jaws may be free to swing upon their pivoted connection with the draw-head to the position shown on the right in Fig. 6, each heel f is beveled off at g , and in order that the locking-dog may not strike against a sharp projection or shoulder when being forced forward into the recess between 80 the heels I bevel the heel of the jaw B, as shown at h , while the heel of the jaw B' is rounded off at h' , this construction being clearly shown in the figures last referred to.

The locking-dog C is provided with a shank, 85 k , which runs through an aperture formed in a partition, l , of the draw-bar A, the dog being held forward and within the recess i by means of the spiral spring m . In order that the locking-dog may be withdrawn from its 90 normal position in the socket i , I provide such a mechanism as is best illustrated in the first four figures of the drawings.

The dog C is provided with a cross-bar, D, which extends through slots formed through 95 each side of the draw-head.

Just at the point where the draw-head A' branches out from the draw-bar A there is a lug, n , and to this lug there is pivoted a U-shaped lever, N, which projects forward from 100 its pivotal connection with the lug n , and is connected to each end of the bar D by links o . From the center of the U-shaped portion of the lever N there extends an arm, p , which

is provided with a weight, p' , and the lower end of this arm p is connected by a chain, q , to a shaft, O , which extends across the end of the car, each end of the shaft being provided 5 with a hand-wheel, as P . A second chain, q' , extends from the end of the arm p to the lower end of a vertical shaft, P' , which is secured in bearings fixed to the end of the car and extends upward slightly above the car-roof.

10 The coupling-link M , used with such a coupling as has been described, consists of a shank, r , upon each end of which there is a ball, R , so proportioned as to fit snugly within the spherical recess formed by the recesses $b b$.

15 The operation of this coupling is as follows: The coupling-link M having been inserted between the jaws $B B'$ of one of the cars to be coupled, and the locking-dog C having been advanced within the recess i , so as to prevent 20 the jaws from swinging upon their pivotal connection, the cars to be coupled are brought together, and as they approach the extending ball R of the coupling-link M will strike against the bell-shaped mouth d of the lower 25 jaw, B' , of the car, to which the first car named is to be coupled, because, as will be well understood, the force of gravity will draw the coupling-link M to substantially the position shown in Fig. 5. As the cars continue 30 to approach the ball R will slide up the bell-shaped mouth-piece until the coupling-link and the opening jaws will be about in the position shown in Fig. 6, when any continued approach to the cars will cause the ball to 35 enter the recesses $b b$, after which the jaw B will drop down so that its lower edge will be about in a horizontal plane, and the lower jaw, B' , will be raised when the ball R strikes against its inner rear face, v . When the parts are in 40 this position, the spring m will act to force the locking-dog C forward within the recess i , thereby locking the jaws and preventing them from spreading to release the ball R . When 45 it is desirable to uncouple the cars, either the shaft O or the shaft P will be rotated to wind

up the chains $q q'$, which winding of the chains will move the lever N to the position shown in dotted lines in Fig. 2, thus withdrawing the dog C from the recess i and leaving the jaws $B B'$ free to swing upon their pivoted 50 connections e . In order that cars provided with this coupling may be coupled with cars provided with the old form of pin-and-link coupling, I provide each of the jaws $B B'$ with an aperture, as s , through which the coupling-pin may be inserted, a coupling-link of the ordinary construction being used at this time.

The balls $R R'$ will have all necessary play within the recesses of the locking-jaws, owing to the form of the mouth-pieces d . 55

Having thus fully described my invention, what I claim as new, and desire to secure by Letters Patent, is—

1. The combination, with a draw-head formed with a recess, a , of pivotally-mounted 65 coupling-jaws provided with recesses $b b$ and heels f , having recesses i , a locking-dog, C , and a manipulating mechanism, substantially as described.

2. The combination, with a draw-head, of 70 two locking-jaws formed with recesses b , flaring mouth d , heels f , provided with recesses i , pivot-pin e , a locking-dog, C , spring m , lever N , chain q , and shaft O , substantially as described.

3. The combination, with a draw-head formed with a recess, a , of the locking-jaws $B B'$, the jaw B being formed with a heel, f , and beveled faces g and h , while the jaw B' is formed with a beveled face, g' , and curved face h' , the 80 two jaws being held to the draw-head by pivot-pins $e e$, a locking-dog, C , formed with a shank, h , spring m , a lever, N , pivotally mounted on the draw-head and connected by a link, o , to the bar D of the locking-dog, a chain, q , and 85 a shaft, O , substantially as described.

CLIFTON T. CHAPPELL.
